DESIGN FOR A DISPLAY RACK

Edward Paul May, New Brighton, Pa.

Application February 10, 1939, Serial No. 82,915

Term of patent 3½ years

To all whom it may concern:

Be it known that I, Edward Paul May, a citizen of the United States, residing in New Brighton, in the county of Beaver, State of Pennsylvania, have invented a new, original, and ornamental Design for a Display Rack, of which the following is a specification, reference being had to the accompanying drawing, forming a part thereof.

The figure is a perspective view of a display rack, showing my new design.

I claim:

The ornamental design for a display rack, as shown.

EDWARD P. MAY.
